STAPLING MACHINE

Maurice Charles Glennon, 15 Hornshay St.,
London, England

Filed July 29, 1968, Ser. No. 12,931

Claims priority, application Great Britain Apr. 9, 1968

Term of patent 14 years

Int. Cl. D8—02

U.S. Cl. D8—49

Fig. 4.

FIG. 1 is a perspective view of a stapling machine showing my new design;

FIG. 2 is an elevation of the other side;

FIG. 3 is an elevation of the end opposite to that seen in FIG. 1; and

FIG. 4 is a bottom plan view thereof.

I claim:

The ornamental design for a stapling machine, substantially as shown.
